UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

CORRUGATED-SHEET-METAL CAR.

1,224,777.

Specification of Letters Patent.

Patented May 1, 1917.

Application filed December 24, 1915. Serial No. 68,587.

To all whom it may concern:

Be it known that I, ALLEN E. OSTRANDER, residing at Ridgewood, Bergen county, New Jersey, and being a citizen of the United States, have invented certain new and useful Improvements in Corrugated-Sheet-Metal Cars, of which the following is a full, clear, and exact description, such as will enable others skilled in the art to which it appertains to make and to use the same, reference being had to the accompanying drawings, which illustrate the preferred form of the invention thought it is to be understood that the invention is not limited to the exact details of construction shown and described, as it is obvious that various modifications thereof will occur to persons skilled in the art.

In said drawings:

20 Figure 1 is a side elevation of approximately one half the car, a portion being broken away to show the inside sheet.

Fig. 2 is an enlarged substantially half transverse section, taken on line 2—2 of Fig. 1, an intermediate portion being omitted.

Fig. 3 is an enlarged central longitudinal section of an end portion of the car taken on line 3—3 of Fig. 2, with an intermediate portion omitted, and

Fig. 4 is an enlarged horizontal section taken along line 4—4 of Fig. 1, intermediate portions being omitted.

It is the object of the present invention to provide a construction for cars, and particularly that type known as box cars, which shall have a superstructure which renders the use of the usual side and end framing, carlines and purlins unnecessary.

40 By virtue of the properties of corrugated sheets and the proper arrangement and association of a plurality of them, the side and end walls and the roof possess inherent self-sustaining qualities, and result in a car having a minimum number of parts.

Another object is the incorporation of side and end sills in the side and end walls of the car, or of the end sills in the end walls alone, or of the side sills in said side walls alone, with independent structural sills substituted where the incorporation does not occur.

Still another object is the prevention of rain or snow entering between the associated

sheets and the consequent lessening of their lives due to ferrous disintegration.

Referring now to the drawings, 1 indicates parallel channels, of a length substantially equal to the car length, and disposed on each side of the longitudinal center line of the car, said channels constituting the center sills. The end portions thereof in conjunction with draft sill extensions 2 form the draft sills.

Said draft sill extensions 2 are attached to the channels 1 and are in the form of channel pressings which extend under and project outside of the end walls of the car and assist in supporting striking plate castings 3. Draft sill extensions 2 also coöperate with said striking plate castings and carry irons 3^a in positioning and supporting the coupler shank (not shown).

As shown in Figs. 1 and 4, the usual bolsters A, floor beams B and cross bearers C are disposed transversely of the center sills 1, and at their outer extremities support side sills 4, here shown as channels. Transversely disposed end sills, to be later described, connect the ends of said side sills.

Each side wall of the superstructure comprises a plurality of conterminous corrugated metal sheets, preferably a pair, the arches and furrows of the outside sheet 5 being vertically arranged, while those of the inside sheet 6 have a horizontal disposition. The vertical corrugations of sheet 5 resist flexure of sheets 5 and 6 from the vertical, flexure of said sheets in a horizontal direction being opposed by the horizontal corrugations of sheet 6.

The furrows of sheets 5 and 6 contact at regular intervals, and some of the points of contact of said furrows are electrically or otherwise welded. These welds 7 are usually arranged in diagonal lines, or lines corresponding to the positions of the usual, but omitted, side framing elements, such as diagonal braces. The resulting wall is rigid, strong, self-braced and self-sustaining.

Each end wall is similarly constructed, having an outside sheet 8 and inside sheet 9, both being corrugated and conterminous, with the corrugations arranged as in the side walls, and said end walls have all the properties and advantages of the side walls.

A roof, preferably, but not necessarily, arched, is likewise constructed of conterminous

ous corrugated sheets, the corrugations of an outside sheet 10 crossing the corrugations of its associated inside sheet 11, and the other details of construction substantially correspond to those of the side and end walls.

Outside and inside sheets 5 and 6, respectively, of the side walls each extend to the bottom of side sills 4, the horizontally disposed corrugations of the inside sheet not extending below the floor line, nor above the bottom of internal side plates 12. The outer faces of the lower uncorrugated portions of inside sheets 6 contact with the furrows of outside sheet 5, and rivets 13 pass through the metal of the furrows of sheets 5, the lower uncorrugated portions of sheets 6 and the webs of side sill channels 4, securing them together. The upper uncorrugated portion of each inside sheet 6 also contacts with the furrows of its associated outside sheet 5, and rivets 14 pass through both said sheets and the internal side plate 12, binding these elements in permanent relationship.

In each end wall, the corrugations of inside sheet 9 do not extend below the floor line, nor above the bottom of the internal end plate 15. The outside sheet 8, inside sheet 9 and the end plate 15 are fastened to each other by rivets 16.

It is well within my conception to arrange the side and end sills, as well as the side and end plate, on the exterior of the side and end walls in instances where it is advantageous to do so. No limitation is, therefore, to be construed by the reference to these parts which designates them as internal members.

Along the lower horizontal edge of sheet 9 of each end wall is secured thereto and to sheet 8, by rivets 17, an angle 18, and parallel therewith but spaced above said angle is another similar angle 19, also secured to said sheets 8 and 9 by rivets 20. Angle 19 is the top chord and angle 18 the bottom chord of the end sill, and the lower portions of sheets 8 and 9 constitute the web of said sill. Obviously, such a construction may be substituted for the side sill channels 4, if desired.

Said end sills and the side sills 4 are joined at the corners formed by their meeting ends by flanged gussets 21.

Rivets 13 bind one flange of each gusset plate 21 to the side sills 4, while rivets 20 secure another gusset flange to the angle top chord 19 of the end sill. Outside of the vertical end edge portions of the side and end walls are vertical angle corner posts 22, extending from the bottom of said walls to the top thereof. Said walls are secured to each outside corner post by means of rivets 23 passing through one flange of the corner post and sheets 5 and 6 of the side wall, and

also by other rivets 24 passing through the other flange of said corner post and sheets 8 and 9 of the end wall.

The inside faces of the vertical end edge portions of the side and end walls are joined by connection angles 25, a vertical line of bolts 26 passing through one flange of each of said outside corner posts, portions of side wall sheets 5 and 6 that are channeled by their arches and furrows, and one flange of the connection angle 25 associated with each corner post, and another vertical row of bolts 27 passes through the other flange of each of said outside corner posts, similarly channeled portions of sheets 8 and 9, and the other flange of said interior connection angles 25. Thus, the vertical end edges of the side and end walls are embraced by or pocketed between said corner posts and corner connection angles and riveted to the first and clamped between both.

The corner posts 22 are each connected at their lower extremities to the ends of the side sills by the two lowest of the rivets 23 and by rivets 28 which pass through one flange of said corner post 22, sheets 5 and 6 of the side wall and the web of the side sill channel 4, and to the ends of the end sills by the two lowest of the rivets 24 and by rivets 29.

The rivets 24 which secure the end wall-lapping flange of each of the posts to the end sills may be countersunk because of the push pole pocket casting bearing against said flange and said rivets 24 pass through said flange, sheets 8 and 9 of said end wall and the vertical flanges of the top and bottom chord angles, 19 and 18 of the end sill. One rivet 24 passes through flange of gusset 21. Rivets 29 pass through a flange of said push pole pocket casting and the other parts just enumerated.

In the underframe, the center and draft sill channels 1 are attached to the end sill by angular connection plates 30, crimped to fit said end sill. See Figs. 2 and 3. Intermediate the center and draft sill channels 1 and the side sill channels 4 are longitudinal floor stringers 31, preferably commercial Z-bars, connected to said end sills by angular connection plates 32 crimped to fit said sills.

Resting on the top flanges of the channels 1 are wooden floor stringers or nailing strips 33 and supported upon said wooden stringers 33, Z-bar stringers 31 and the top flanges of side sill channels 4 is a suitable floor 34. The bottom corrugations of the inner sheets of the side and end walls bear on top of floor 34 and hold it down on the top flanges of the side and end sills. A beveled grain strip 35 runs about the boundary of the floor in the angles formed by said floor and the side and end walls, where-

by when the lading is grain, for example, it will not be able to accumulate and remain in the floor corners of the car.

Diagonal braces, running from the corners of the underframe to the center sills, are present in the form of angles 36 attached to gussets 21 and to said center sills 1, the connection to said sills, however, not being shown in the drawings for obvious reasons.

At the top of the car side walls, the internal side plates are flanged, as at 37 in Fig. 2, and form a support for the sides of the roof sheets 10 and 11, which are fastened thereto by bolts 38, said bolts passing through longitudinal clamping strips 39 paralleling the eaves of roof sheets 10 and 11 and the flanges 37 of the side plates. Said side plate flanges 37 and bottom roof sheets 11, when so clamped in place, make closed joints between the side walls and the roof throughout the length of the car.

Internal end plates 15 are also flanged at the top, the flanges 40 extending outwardly and abutting the downwardly directed flanges 41 of roof sheet 10, said flanges 40 and 41 closing all air passages at the top of the end walls that would otherwise lead to the interior of the car. End plate flanges 40 also support the ends of the roof sheets 10 and 11.

On top of the roof is mounted a running board 42 supported upon running board saddles 43, bolts passing through the said running board 42, saddles 43, and roof sheets 10 and 11, binding these elements together. The overhanging ends of the running board are tied together by cleats and braced to the end walls by brace rods 44.

Sheets 5 of the side walls are flanged, as at 45, to close the arches and furrows of its companion sheet, and sheets 8 of the end walls are likewise flanged at 46 for a similar purpose. See Fig. 4.

In general, tight joints between the walls, the roof and floor are provided and the ducts formed by the arches and furrows of the wall and roof sheets are closed, so that the interior of the car is impervious to the weather, as are also the internal surfaces of the corrugated sheets comprising the walls of the car.

The car may readily be converted into the ventilated type that is used for transporting perishable lading by simply preventing the contacting of flanges 37 of the side plates with roof sheets 11, or by leaving spaces between the downturned flanges 41 of roof sheet 10 and the juxtaposed edges of flanges 40 of end plates 15. Also, the car may be ventilated in both manners. To guard against any possible spreading of the walls under the influence of such lading as grain the tops of the side walls are restrained from outward deflection by tie rods or angles 47 illustrated in Fig. 2 as being connected to

said side walls by angular connection plates 48.

When there are to be door openings in the car, the walls, as for example, the side walls, are interrupted to form such door openings 70 and the inner vertical edge portions of the side wall sections are attached to a vertical flange of a door post, the latter being a pressing 49 of J-shaped cross section from which said door post flange extends. Vertical strips 50 are disposed against the inner ends of sheets 6 of the side walls opposite the flanges of the door posts 49, and a vertical line of rivets passes through each strip 50, sheets 6 and 5 of the side wall and said flange of the door post 49, binding them together and pocketing the side wall between the door post flanges and strips 50.

Within pressing 49 is a wooden filler 51, and against it is placed a wooden nailing strip 52 to which a grain door may be nailed, both being secured to the said door post pressing 49 by bolts. See Figs. 1 and 4.

Said door posts are also provided with other short flanges 53 at their lower ends, 90 which are riveted to the webs of the side sill channels 4, and with still further flanges 54 at their upper ends which are attached to a door lintel 57. Threshold plates are provided in the form of angles 55 riveted to the outer faces of the webs of the side sill channels 4.

Push pole pocket castings 56 are secured to the lower corners of the end walls, and both said push pole pocket castings and the striking plate castings are provided with integral ribs 58 having cylindrical bosses, which occupy positions in the furrows of sheets 8 and interlock said castings with the end walls of the car, restraining them from displacement, and further spaces them in advance of sheets 8 so that pressure exerted against said castings will not injure said sheets.

What I claim is:—

1. In a car having an underframe, the combination of side walls and end walls, each comprising a plurality of relatively parallel conterminous sheets, each sheet having spaced apart arches producing channels therein and means for attaching said sheets together and to said underframe, some of said sheets closing the ends of channels of other sheets.

2. In a car having an underframe, the combination of side walls and end walls, each comprising a plurality of relatively parallel conterminous sheets, each sheet having spaced apart arches forming channels therein, corner posts at the corners 125 of said underframe, and means passing through some of the channels joining said side and end walls to said corner posts.

3. In a car having an underframe, the combination of side walls and end walls, 130

each comprising a plurality of relatively parallel inner and outer sheets having spaced apart arches, the arches of contiguous sheets being angularly disposed to each other, a 5 roof, side and end plates extending toward arches of the inner sheets and over the arches of the outer sheets of said side and end walls and in continuous proximity to the upper terminals of the last mentioned 10 arches, said plates supporting said roof.

4. In a car having side and end sills, the combination of side and end walls each comprising a plurality of parallel sheets provided with alternate arches and furrows, 15 said arches and furrows of contiguous parallel sheets being angularly disposed to each other and said furrows contacting and being secured together, said side and end walls being attached, respectively, to said side and 20 end sills, and a floor supported by said sills, some of said arches being parallel therewith and bearing on the top thereof to hold said floor down.

5. In a car, an underframe, corner posts 25 lapping the same and attached thereto, side and end walls supported by said underframe and said corner posts, connection and reinforcing members supplementing said corner posts, said side and end walls each comprising 30 a plurality of conterminous parallel sheets having alternate arches and furrows forming channels in said sheets, those of contiguous parallel sheets crossing each other, and fastening means extending 35 through said corner posts, channels of said sheets and connection members.

6. In a car, suitably connected side and end walls, said end wall comprising a plurality of corrugated sheets, the corrugations 40 of contiguous sheets being angularly disposed to each other, center sills, draft sill extensions projecting beyond the center sills and end wall, an end sill member reinforcing the end wall sheets, a striking plate supported 45 by said extensions and projecting between corrugations of one of the end wall sheets, connection members extending between said center sills and end wall, and means connecting the end wall sheets securing 50 said striking plate and end sill and connection members thereto.

7. In a car having an underframe, side and end walls attached thereto, each comprising a couple of parallel conterminous 55 sheets, each sheet having alternate arches and furrows that are angularly disposed to those of its associated sheet, flanges at opposite ends of one sheet of each wall serving as closures for the arches and furrows of its companion sheet, and corner posts and corner connection angles embracing the vertical ends of and securing together said side and end walls.

8. In a car, a metallic side wall comprising 65 a plurality of relatively parallel con-

terminous corrugated sheets, the corrugations of one being angularly disposed to those of the next contiguous sheet, an underframe having a side sill to which said side wall is attached, a corner post, means securing said side wall thereto and to said underframe, a sheet metal door post embracing a wooden filling serving as a nailing strip and means co-acting with said metal door post to pocket and retain the adjacent edge 75 of the corrugated side wall.

9. In a metallic car, an underframe, spaced upstanding posts attached thereto, a wall comprising a plurality of relatively parallel conterminous sheets having alternate 80 uniformly spaced apart arches and furrows, those of one sheet being angularly disposed to those of the next contiguous sheet, said furrows of said parallel sheets contacting at regular intervals and being spot welded at 85 certain of the contacting points of the furrows, binding members paralleling and clamped to said posts by means passing through the wall sheets, said sheets extending between said posts and members with the 90 arches of the sheet next to said members intermittently contacting with the latter substantially throughout their widths.

10. In a car, a wall comprising a plurality of relatively parallel conterminous sheets, 95 each of which has a series of alternating arches and furrows angularly disposed to those of its companion sheet, the furrows of said parallel sheets contacting intermittently, and vertically spaced compression and tension members secured to and extending across the lower portion of said wall and forming therewith a sill stiffened by some of said arches.

11. In a car having an underframe, metallic side and end walls each comprising a plurality of relatively parallel conterminous sheets, alternately arched and furrowed, the arches and furrows of each sheet crossing those of its companion sheet, said parallel sheets being suitably connected at such points as will resist stresses which tend to distort or deflect said walls, a roof, flanges rigidly combined with and extending from some of the wall sheets across the terminals 115 of the arches and furrows of the next contiguous sheets, excluding moisture from between parallel sheets and the wall sheets and said roof, and means connecting said side and end walls together and to said underframe.

12. In a car, an underframe, a metallic end wall comprising a couple of parallel conterminous corrugated sheets, the corrugations of one sheet crossing those of the other, 125 means attaching said side and end walls together and to said underframe, a push pole pocket member having integral projections interlocking with corrugations of said end wall, and means connecting said end wall 130

- sheets and holding said push pole pocket member in place.
13. In a car, an underframe, corner and door posts connected thereto, and metallic side and end walls connected to said posts and underframe without reinforcement intermediate said posts, each of said walls comprising a couple of parallel conterminous sheets having spaced apart arches and furrows, those of one sheet being angularly disposed to those of the other, said furrows contacting at regular intervals and being welded together to give the effect of bracing framing.
14. In a car having an underframe, side and end walls attached to the underframe, and end walls having door openings therein, said side and end walls each comprising relatively parallel conterminous sheets, the corrugations of one sheet being angularly disposed to those of its companion sheet, flanged side plates, flanged end plates increasing in vertical dimension toward the vertical median lines of said end plates, fastening means along the upper and lower edges of said end plates securing the latter to said parallel end wall sheets and a roof supported on the flanges of said side and end plates.
15. In a car, side and end walls each comprising a couple of relatively parallel conterminous corrugated sheets, the corrugations of one sheet crossing those of its companion sheet, side sills with which said side walls are connected, and end sills of which said end walls are necessary parts.
16. In a car, side and end walls, each comprising a couple of relatively parallel conterminous corrugated sheets, the corrugations of one sheet crossing those of its companion sheet, a roof, side sills, end sills of which said end walls are necessary parts, and tie rods connecting the upper portions of said side walls together.
17. In a car, side and end walls each comprising a couple of relatively parallel conterminous corrugated sheets, the corrugations of one sheet crossing those of its companion sheet, a roof, an underframe comprising side sills to which the side wall sheets are connected, end sills of which said end walls are necessary parts, a floor positioned by corrugations of some of said sheets, and grain strips filling the angles formed by said side and end walls and said floor.
18. In a car, an underframe, side and end walls each comprising a plurality of relatively parallel conterminous sheets secured together, each sheet having properties tending to neutralize the bending of itself and its companion sheet in a direction different from the direction of resistance of said companion sheet, a roof, said roof and side and end walls being supported upon said underframe, portions of said underframe being portions of said wall sheets.

In witness whereof I have hereunto set my hand in the presence of two witnesses.

ALLEN E. OSTRANDER.
